DISPOSABLE BLOOD LANCET

Irving A. Speelman, Brooklyn, N. Y., assignor to Propper Manufacturing Company, Inc., Long Island City, N. Y., a corporation of New York

Application October 12, 1954, Serial No. 32,638

Term of patent 14 years

(Cl. D83—1)

FIG.1.

FIG.2.

FIG.3.

FIG.4.

Figure 1 is a perspective view of a disposable blood lancet, embodying my new design;

Figure 2 is a top plan view;

Figure 3 is a side elevational view;

Figure 4 is a fragmentary, enlarged perspective view of the skin-puncturing end of the lancet.

The opposite side of the disposable blood lancet is substantially the same as the side shown except for the protruding structure shown in Figure 2.

I claim:

The ornamental design for a disposable blood lancet, substantially as shown and described.
